(57) **CLAIM**

The ornamental design for a motion detector camera, as shown and described.

DESCRIPTION

FIG. 1 is a perspective view of a motion detector camera, incorporating the new design;

FIG. 2 is a front view of the motion detector camera of FIG. 1;

FIG. 3 is a back view of the motion detector camera of FIG. 1;
FIG. 4 is a left side view of the motion detector camera of FIG. 1;

FIG. 5 is a right side view of the motion detector camera of FIG. 1;

FIG. 6 is a top plan view of the motion detector camera of FIG. 1; and,

FIG. 7 is a bottom plan view of the motion detector camera of FIG. 1.

The broken line portions are shown to illustrate environment only and form no part of the claimed design.
